UNITED STATES PATENT OFFICE.

CHARLES D. KLINE AND EDWARD NALL, OF AKRON, OHIO, ASSIGNORS TO THE GOOD-YEAR TIRE AND RUBBER COMPANY, OF AKRON, OHIO, A CORPORATION OF OHIO.

SHOE FOR LADDERS.

1,113,446.

Specification of Letters Patent.

Patented Oct. 13, 1914.

Application filed May 23, 1914. Serial No. 840,503.

To all whom it may concern:

Be it known that we, CHARLES D. KLINE and EDWARD NALL, citizens of the United States, residing at Akron, in the county of Summit and State of Ohio, have invented new and useful Improvements in Shoes for Ladders, of which the following is a specification.

This invention relates to improvements in ladder shoes for holding the lower ends of a ladder against slipping, and the object thereof is to provide a strong, secure and efficient device which can be readily attached to a ladder and removed therefrom and which possesses unusual gripping properties for engagement with the floor or other surface on which the ladder rests.

With the foregoing and other objects in view, the invention consists in the novel construction, combination and arrangement of parts constituting the invention to be hereinafter specifically described and illustrated in the accompanying drawings which form a part hereof wherein is shown the preferred embodiment of the invention, but it is to be understood that changes, variations and modifications can be resorted to which come within the scope of the matter hereinafter claimed.

In the drawings in which similar reference numerals indicate like parts in the different figures, Figure 1, is a view in side elevation of a ladder provided with ladder shoes embodying this invention shown in operative position with respect to a floor and upright structure; Fig. 2, is a view in front elevation of the device shown in Fig. 1; and, Fig. 3, is an end elevation of one of the shoes enlarged, with portions thereof in section to better illustrate the construction thereof.

In the description and claim, the word "floor" will be used generically to designate the surface on which the ladder rests, but no limitation is intended by the use of this designating word.

In the drawings, the reference numerals 1 and 2 denote respectively a floor and an upright structure against which the ladder is adapted to be placed. The ladder consists of the usual stiles 3 provided with rungs 4. The lower ends of the stiles of the ladder are provided with transverse openings with the axes thereof preferably in alinement with each other. Adapted to be secured to

each of the stiles is a ladder-shoe and as they are identical a description of one is believed to be sufficient.

The shoe embodies a body portion 5 provided with a pair of upwardly-extending lugs 6 in which are transverse alined apertures 7 to receive bolts, studs, pins, or other hold-fast devices 8 for pivotally attaching them to the lower ends of the stiles 3. The lugs 6 are arranged in spaced relation to permit the positioning of the lower end of the stile between the members of each pair. The central part of the body portion 5 extends downwardly at 9 and is provided at the marginal portions with flanges 10 positioned above the plane of the lower face of the projecting portion 9. The flanges 10 are provided with threaded apertures 11 for a purpose to be later described. The under face of the body portion 5 is provided with a covering 12 consisting of one or more layers of vulcanized cellular rubber, such for instance, as sponge rubber, and this covering 12 of rubber is carried laterally over the under faces of the flanges 10 and is held in position through the medium of metallic strips 13 applied to the under face of those portions of the covering 12 which lap or extend over the under faces of the flanges 10. The strips 13 are clamped against the rubber covering 12 through the medium of hold-fast devices, such for instance, as screws 14. By placing the flanges 10 and the clamping strips 13 above the plane of the floor it keeps all metal from engagement with the floor and presents to the floor on which the ladder is rested only the cellular rubber covering of the median portion of the shoe so as to provide a gripping surface for the engagement with the floor. The sponge rubber provides an unusually efficacious and satisfactory gripping surface in connection with these ladder-shoes in that they grip a wet or otherwise slippery floor much more securely than would be possible were any other material employed, and in fact, more securely than if the ends of the stiles of the ladder are provided with sharpened points, as is now the customary manner of holding a ladder against slipping.

We claim:

A ladder shoe comprising a body portion of rigid material and provided with means for pivotally attaching it to a ladder stile, said body portion provided with a central

depending portion and further provided with a pair of lateral flanges positioned above the plane of the central portion of the shoe, a covering of vulcanized cellular rubber extending transversely from side to side of the under face of the shoe and covering the central depressed portions to provide a gripping surface and extending laterally over the under faces of said lateral flanges, and hold-fast devices engaging said cover-

ing and said flanges for securing said covering in position.

In testimony whereof we have hereunto set our hands in presence of two subscribing witnesses.

CHARLES D. KLINE.
EDWARD NALL.
